W. BABEKUHL

LOCK FOR RAILROAD CARS

Filed Nov. 1, 1926

FIG. 1.

五五三 2

FIG. 4.

FIG. 3.

INVENTOR:

WILLIAM BABEKUHL,

By: Otto J. Kueger,
his Atty.

UNITED STATES PATENT OFFICE.

WILLIAM BABEKUHL, OF LOS ANGELES, CALIFORNIA.

LOCK FOR RAILROAD CARS.

Application filed November 1, 1926. Serial No. 145,558.

This invention relates to devices used on the sliding doors of railroad-cars, more particularly on freight-cars.

One of the objects of this invention is to provide a lock of simple construction, easily applicable to the doors of train-cars including a pawl to drop behind the edge of a door-jamb and a latch-bolt to hold the pawl in closed position.

Another object is to provide a pivotally mounted pawl disposed to swing in a vertical plane out of the flat side of a door for locking purposes and adapted to withdraw behind the surface of a door in operative position.

Another object is to provide a worm gear actuating mechanism for such a pawl.

Another object is to provide a latch-key operated lock-bolt disposed to slide over such a pawl in locked position.

Other objects will appear from the following description and appended claims as well as from the accompanying drawing, in which—

Fig. 1 is a fragmentary somewhat diagrammatic illustration in top plan view of a lock embodying this invention in operative relation to a sliding door and the jamb of a railroad-car, the jamb and door being shown in a horizontal section.

Fig. 2 is a vertical section through the lock on line 2—2 of Fig. 3 illustrating the pawl in locking position, the operating or actuating mechanism being cut away.

Fig. 3 is a horizontal section through the lock approximately on line 3—3 of Fig. 2, illustrating the worm gear actuating mechanism in operative connection with the pawl.

Fig. 4 is a perspective illustration of the worm gear actuating mechanism in connection with the pawl, and the latch-mechanism somewhat disconnected.

The sliding doors of railroad-cars, as a rule are mounted to slide over the outside of the car-body as illustrated in Fig. 1, the door being indicated at 5 and a door-jamb being indicated at 6. The closing movement of the sliding door is normally in the direction of the arrow 7, so that the rear-edge 8 of the sliding door in closing position remains in slightly overlapping position in relation to the door-jamb 6. By providing a pawl 9 disposed so as to swing

in a vertical plane behind the edge 10 of 55 the jamb 6, the door 5 is prevented from moving from its closed position. A pin 22 is provided in the edge 10 of the jamb 6 over which the pawl 9 is made to engage to prevent even a lifting of the sliding door away 60 from the front-surface of the side of the railroad-car. This pawl 9 is mounted on a shaft 11 together with a worm gear 12 by which the pawl can be controlled in its swinging movements. A worm 13 operative by a socket-handle 14 is disposed so as to allow an actuating of the worm gear and pawl from the front-side of the door. A latch-mechanism 15 is embodied in the lock-structure including a latch-bolt 16 which by 70 means of the latch-key 17 allows a locking of the pawl 9 in closed position.

A lock-casing 18 is recessed within the door 5 as illustrated in Figs. 2 and 3. This casing is formed as indicated at 19 to receive the pawl 9 in closed position, so that the side 20 of the pawl is disposed flush with the rear-side 21 of the door in such inoperative position of the pawl. As stated above, the pawl 9 is mounted on the shaft 80 11 together with the worm gear 12 within the lock-casing 18. The set screw 23 serves to facilitate a mounting and setting of the pawl on the shaft 11. The pawl and worm gear are in this manner mounted in the 85 same level. The worm 13 is mounted below the worm gear and is provided with a key-end 24 terminating below the front-side 25 of the door. A hole 26 is provided in the front-side to allow an insertion of the 90 socket-handle 14 over the key-end 24 of the worm-shaft. The latch-mechanism is mounted within the lock-casing with the lock-bolt 27 disposed just above the pawl 9 in the closing position of the pawl as indicated in Fig. 2.

By inserting the socket-handle 14 into the hole 26 over the key-end 24 of the worm, the pawl can be swung in a vertical plane back and forth into locking and into operative position.

When the pawl is turned into locking position, the latch or lock bolt 27 can be moved by the key 17 to shift over the pawl 9 for holding the pawl in locking position. 105

When the pawl is locked in this manner with its hook-end 28 engaged over the pin 22, the door 5 is firmly locked against move-

ments past the jamb 6 and also firmly locked to the jamb by the interengagement of the hook 28 to the pin.

Having thus described my invention, I claim:

1. In a freight-car lock, a pawl mounted to swing in a normally vertical plane to extend out of the inner side of a car door and adapted to withdraw to within the body of the door in inoperative position, a gear mechanism in operative connection with said pawl having key supporting means by which the pawl can be operated, and a latch-key operated bolt disposed to shift over the top of the pawl when the pawl is in locking practically horizontal position projecting out of the side of the door for locking the pawl in this position against swinging movements.
2. In a freight-car lock, in combination

with the jamb and the door of a freight-car, a pawl mounted in said door to swing in a normally vertical plane to extend out of the inner side of said door so as to project beyond the edge of the jamb when the door is in closed position, a pin in the edge of the said jamb, the pawl having a cut-out near its free end to engage over the said pin in locking position, a gear mechanism in operative engagement with said pawl and embodying a key-supporting end below the outer side of said door by which the pawl can be swung and operated, and a latch-key operated bolt within said door disposed to shift over the top edge of the said pawl when the pawl is in locking position.

In testimony that I claim the foregoing as my invention I have signed my name.

WILLIAM BABEKUHL.
